(57) **CLAIM**

The ornamental design for poker chip, as shown and described.

DESCRIPTION

FIG. 1 is a front bottom perspective view of a first embodiment of the poker chip;

FIG. 2 is a front elevational view, the rear elevational view being a mirror image thereof;

FIG. 3 is top plan view, the bottom plan view being a mirror image thereof;

FIG. 4 is a left side elevational view, the right side elevation view being a mirror image thereof;

FIG. 5 is a front bottom perspective view of a second embodiment of the poker chip;

FIG. 6 is a front elevational view, the rear elevational view being a mirror image thereof;

FIG. 7 is top plan view, the bottom plan view being a mirror image thereof; and,

FIG. 8 is a left side elevational view, the right side elevation view being a mirror image thereof.

The broken lines in the figure drawings represent environmental structure and form no part of the claimed design.
